(57) **CLAIM**

The ornamental design for an adaptor for a blind system, as shown and described.

DESCRIPTION

FIG. 1 is a perspective view of an adaptor for a blind system; FIG. 2 is a front view thereof; FIG. 3 is a rear view thereof; FIG. 4 is a left side view thereof; FIG. 5 is a right side view thereof; FIG. 6 is a top view thereof; and, FIG. 7 is a bottom view thereof.

The broken lines in the drawings depict portions of an adaptor for a blind system that form no part of the claimed design.

See application file for complete search history.
